(57) **CLAIM**

The ornamental design for a light emitting diode, as shown and described.

DESCRIPTION

FIG. 1 is a perspective view of the light emitting diode in accordance with an embodiment of our new design;

FIG. 2 is a top plan view of the light emitting diode in accordance with the embodiment of our new design;

FIG. 3 is a front elevational view of the light emitting diode in accordance with the embodiment of our new design;

FIG. 4 is a left side elevational view of the light emitting diode in accordance with the embodiment of our new design;

FIG. 5 is a rear elevational view of the light emitting diode in accordance with the embodiment of our new design; and,

FIG. 6 is a right side elevational view of the light emitting diode in accordance with the embodiment of our new design.

The bottom plan view of the light emitting diode is omitted because the bottom surface of the light emitting diode is flat and devoid of surface ornamentation.
